UNITED STATES PATENT OFFICE.

EDMUND J. OGDEN, OF SPRINGFIELD, ILLINOIS.

DESIGN FOR A MOCCASIN.

49,733.

Specification for Design.

Patented Oct. 3, 1916.

Application filed July 6, 1916. Serial No. 107,861. Term of patent 14 years.

To all whom it may concern:

Be it known that I, EDMUND J. OGDEN, a citizen of the United States, residing in Springfield, in the county of Sangamon and State of Illinois, have invented a new, original, and ornamental Design for Moccasins, of which the following is a specification, reference being had to the accompanying drawings, forming a part thereof.

Figure 1 is a side elevation of a moccasin,

showing my new design; and Fig. 2 is a front view of my moccasin, showing my new design.

I claim:

The ornamental design for a moccasin, as shown.

EDMUND J. OGDEN.

Witnesses:

JAMES REILLY,

RALPH GUSSWEIN.
